UNITED STATES PATENT OFFICE.

JOSEPH P. MERRIAM, OF SANDUSKY, OHIO.

MACHINE FOR DRIVING AND PULLING STAKES AND HANDLING THE SAME.

SPECIFICATION forming part of Letters Patent No. 449,374, dated March 31, 1891.

Application filed July 5, 1890. Serial No. 357,860. (No model.)

To all whom it may concern:

Be it known that I, JOSEPH P. MERRIAM, a citizen of the United States, residing at Sandusky, in the county of Erie and State of Ohio, 5 have invented certain new and useful Improvements in Machines for Driving and Pulling Stakes and Handling Same; and I do declare the following to be a full, clear, and exact description of the invention, such as will 10 enable others skilled in the art to which it appertains to make and use the same, reference being had to the accompanying drawings, and to the letters of reference marked thereon, which form a part of this specification.

15 My invention relates to machines for driving and hoisting piles, stakes for fish-nets, mooring-posts, and the like; and it consists in certain combinations and arrangements of parts, as hereinafter set forth, and particularly pointed out in the claims.

20 In the drawings, Figure 1 is a perspective view of a flat boat or gondola equipped with my improved machine. Fig. 2 is a section on line 2 2, Fig. 3. Fig. 3 is a side elevation, 25 partly in section, on line 3 3, Fig. 4; and Fig. 4 is a top plan view.

My machine can be mounted upon any suitable foundation or support, either floating 30 upon the water, as illustrated, or resting upon the land or on a dock or other structure. It is especially designed, however, for the use of fishermen in setting stakes for weirs, traps, and other nets. It may be driven by the engine used to propel the boat or by an independent motor, as desired. The power may 35 be transmitted in any convenient manner, as by a shaft A, extending from the engine to the machine. A bevel-pinion a on said shaft is engaged by a bevel-gear B, secured to a shaft C, extending transverse of the frame-work D of the machine. The engine is preferably a reversible one, so that the shaft C can be rotated in either direction at will.

Secured upon the shaft C is a gear-wheel c, 45 which meshes with a similar gear e on a shaft E, parallel with and above the shaft C. On this shaft is fastened a face-plate or disk F, and at a little distance from it is a similar face-plate F', the latter being splined upon 50 the shaft, so as to be capable of some axial movement thereon. Between these face-plates is a spool G, loosely mounted on the

shaft, and provided at one end with an annular groove for the reception of a friction band-brake g, controlled by a handle G'. 55

The movable face-plate F' is provided with an arrangement for sliding it along the shaft. I prefer to use a toggle-joint lever F², one link of which is pivoted to an abutment d, rising from the frame-work D, the other end being 60 pivotally attached to a loose collar f, seated in a groove in the hub of the face-plate. An ear f', projecting from the collar, affords a convenient point of attachment for the toggle, and also serves to keep the collar from 65 rotating with the face-plate, being received in a notch cut in the upper edge of the bracket or arm d', fastened to the frame-work D and extending up around or near to the shaft E. A connecting-rod f² runs from the joint 70 of the toggle to an operating-handle f³. When this handle is pulled back, the toggle is extended, and the face-plate F' is forced against the end of the spool. A continuance 75 of the movement slides the spool against the fixed face-plate F, and the friction between these plates and the ends of the spool causes the latter to revolve with the shaft E until released by a forward movement of the handle F³. 80

Upon the spool G is wound the rope H, which runs over a pulley I at the top of the shears K, erected at or near the bow of the boat, and thence to the hammer L, which may be of any suitable construction and arranged 85 to slide vertically between guides. I prefer to use as guides the metallic bars k, secured to the inner edges of the shears. To the shank l of the hammer are fastened transverse cleats l', which overlap the guides on each side and 90 serve as gibbs. Filling-pieces l² may be used, if necessary, between the shank and the guides.

The deck and framing of the boat are cut away between the shears, forming a recess in 95 the bow of the boat, as shown. This permits the shears to be brought on either side of the pile or stake X and helps to steady the boat while the pile is being driven.

In front of the shaft E is a shaft M, extending across the frame-work D over the recess in the boat. Secured upon this shaft is a drum N, on which is wound a heavy hawser O, terminating in a strong hook or grapple o. 100

On one or both ends of the shaft outside of the frame-work D is a large spur-gear m . In the rear of these wheels is a counter-shaft P, which is capable of sliding axially in its bearings. A lever P' , fulcrumed in a bracket d' , has an eye p , encircling the shaft. By means of the lever the shaft can be moved lengthwise in its bearings, the range of movement being sufficient to engage or disengage the pinions p^2 with the spur-gears m . At the same time a gear p^3 on the shaft P is caused either to mesh with or slide away from a pinion c' , secured upon the shaft C.

Instead of arranging the shaft P to slide axially to engage with a fast pinion on the shaft C, I may use a loose pinion meshing permanently with the gear p^3 and provided with a clutch actuated by a lever B', whereby the pinion can be coupled to the shaft C when it is desired to operate the stake-puller. This lever is shown in dotted lines in Figs. 3 and 4. On the ends of the shaft E, I may place gipsy ends or warping-heads E', by means of which the boat can be brought to the place where she is to be moored.

The operation of my machine is as follows: The pile having been brought alongside is hoisted by a rope (not shown) running over a snatch-block I' and down to one of the warping-heads E'. When the pile has been placed between the shears, the handle F³ is thrown back, thereby clutching the spool G to the shaft E and winding up the rope H. When the hammer is raised high enough, it can be held by the friction-band while the handle F³ is thrown forward, releasing the spool and leaving it ready to drop the hammer when the friction-band is slackened off; or the friction-band need not be used at all, the hammer being raised and dropped repeatedly by simply manipulating the toggle-clutch lever F³, the engine and the shafts C E running continuously. In this way the piles or stakes can be rapidly driven at the desired places. When a stake or pile is to be pulled up, the hook or grapple o is attached to it. The engine is then reversed and the counter-shaft P is slid endwise to cause the pinions p^2 and gear p^3 to mesh with the spur-gears m and pinion c' , respectively, which causes the shafts P and M to rotate, winding up the hawser O on the drum N, and so pulling up the pile. The drum can be stopped or started by simply throwing the gears on the counter-shaft out of or into mesh

without stopping the shaft C. When a loose pinion is used, the drum can be started and stopped by the clutch on the shaft C, controlled by the lever B'. If the machine is to be used, with a non-reversing engine, the rope H must be carried under the spool G, as indicated by dotted lines in Fig. 3.

The gipsy ends E' are of great convenience in loading material on board the boat, handling it when needed, and other operations besides those previously mentioned.

Having thus described my invention, what I claim, and desire to secure by Letters Patent, is—

1. An organized machine for driving and pulling piles and the like, consisting of a boat provided with the shaft E, of the face-plates F F', the spool G, the collar f, the toggle-lever F², connected with the collar f, and the handle F³ for operating the toggle, substantially as described.

2. The combination, with the shaft E, of the face-plate F, secured thereto, the face-plate F', splined thereon, the collar f, having the ear f', the toggle F², attached to said ear, the bracket d', having a notch receiving said ear, and the spool G between the two face-plates, substantially as described.

3. In a pile-driver, the combination, with the shears K, having the guides k, of the hammer L, having the shank l, the cleats l', overlapping the guides, and the filling-pieces l² between the shank and the guides, substantially as described.

4. The combination, with a boat having a recess, of the shears K, erected on each side of said recess and serving as guideways for a vertically-movable hammer, substantially as described.

5. The combination, with a boat having a recess, of a hoisting-drum located over said recess, and means for operating said drum, substantially as described.

6. The combination, with a boat having a recess, of the shaft M, extending over said recess and carrying the drum N, and provided with one or more spur-gears m, the shaft C and intermediate gearing connecting the two shafts, substantially as described.

In testimony whereof I affix my signature in presence of two witnesses.

JOSEPH P. MERRIAM.
